United States Patent Office.

JOHN MARTINO, JACOB BEESLEY, AND JOHN CURRIE, OF PHILADELPHIA, PENNSYLVANIA, ASSIGNORS TO C. W. BLANDY AND BROTHER, OF NEWARK, DELAWARE.

Design No. 2,729, dated August 6, 1867; antedated July 16, 1867.

DESIGN FOR A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of the city and county of Philadelphia, and State of Pennsylvania, have invented or originated a new Design for Cook-Stoves, of which the following is a full, clear, and exact description, reference being had to the accompanying photograph, making a part of this specification, in which—

Figure 1 is a perspective view of the stove.

Figure 2 is a like view of the back plate.

Like letters in both figures indicate the same parts.

On the upper rail *a*, of the side A, is the name of the stove, Christiana Cook, having a double scroll ornament, *b*, beneath it, with a curved continuation united with end ornaments *c*. On the lower rail *d* there is a raised panel *e*, with a continued bead and dot ornament *f* around it, and an ornament *g* projecting from each end of the bead ornament. On the panel *e* is the name of the manufacturing firm, C. W. Blandy & Brother, Newark, Delaware. Each oven-door B, has a bead, *b'*, running around it. On the middle portion of the door is an elliptical ornament, *i*, there being an egg-shaped projection, *j*, in the centre, and leaves running therefrom and bordered by a continuous bead and dot ornament, *k*, outside of which there are corner ornaments *l*. The ornamentation of the side fire-doors C is similar to that of the oven-doors B. The same may be said of the ash-pit doors D, with the exception that the transverse axis of the elliptical ornaments is horizontal instead of perpendicular, as on the doors B. The ornamentation of the front fire-doors E is also similar to that of the doors B. There is a vertical ornament, *m*, on each front stile. On the top, in front, each side of the feeder-door, there is a cornucopie ornament, *n*, which has a hinge socket for the feeder-door. The feet F have at top, from the centre each way, a diverging leaf ornament, *o*. Beneath these there is an elliptical leaf ornament, *i'*, with an egg-shaped projection, *j'*, in the centre. At the bottom part of the foot there is a cluster of leaves, *p*, projecting upwards. The back plate G, seen in fig. 2, is raised crosswise, and has a central ornament resembling that on the door B, but considerably flattened. The leaves, however, which radiate from the egg-shaped projection *j''*, are of different configuration. There is on each side of the central ornament a vertical running-leaf ornament, *p'*.

What we claim as our invention, and desire to secure by Letters Patent, is—

The design for cook-stoves, as shown and described.

In testimony whereof we have hereunto set our hands and affixed our seals this 12th day of July, 1867.

JOHN MARTINO. [L. S.]

JACOB BEESLEY. [L. S.]

JOHN CURRIE. [L. S.]
